UNITED STATES PATENT OFFICE

2,617,128

PAD BOX

Charles G. Melanson, Lynn, Mass., assignor to
 United Shoe Machinery Corporation, Flemington, N. J., a corporation of New Jersey

Application March 29, 1951, Serial No. 218,176

12 Claims. (Cl. 12—38)

1

This invention relates to pads and pad boxes for use in machines for applying pressure to shoe bottoms.

Objects of the invention are to provide a pad support which is readily adjustable to the longitudinal contours of shoe bottoms irrespective of the height of the heels the shoes are to have and which is transversely curved to correspond to the transverse curvature of the shank-and-heel portions of shoe bottoms.

To this end the pad support is made in two parts, i. e., a support for the forepart of the pad movable about an axis located substantially in the surface of the pad at the ball line of the shoe and a support for the shank-and-heel portions thereof, said support having a horizontal surface to engage the heel portion and an inclined surface to engage the shank, the support being movable in a direction parallel to the inclined surface to permit adjustment thereof to accommodate shoes that are to have heels of various heights.

As illustrated, the shank-and-heel support comprises a block having a horizontal surface to engage the heel portion of the shoe and an end face inclined at about 45° to the horizontal to engage the shank portion of the shoe, the block being mounted for adjustment in a direction parallel to said end face. Downward adjustment of the block adapts it to accommodate shoes that are to have heels of lesser heights.

Beneath the ball portion of the pad is a fixed support comprising a rod extending transversely of the pad and supported in the walls of an outer box, said rod being linked at its ends to a series of closely adjacent rolls parallel to the rod and forming a roller blanket to lie between the pad and the shank-and-heel portion supporting surfaces of the block. As illustrated, the rolls may be small in the middle and gradually increase in size toward the ends, thus providing a pad-supporting surface which is transversely concave to accommodate the transverse convexity of the shank portion of the shoe bottom. To support the rolls, the surfaces of the block underlying them may be made convex to an extent corresponding to the concavity of the rolls. Thus, the support for the shank and heel portion allows the pad to conform closely to the transverse curvature of the shank-and-heel portion of a shoe bottom. Each roll is a solid generated by the revolution of a conic about an axis in its plane and is therefore a tore. Each roll is mounted for rotation on its longitudinal axis on a rod each end of which is connected to a chain.

2

The support for the forepart of the pad is carried by an inner box and, since adjustment of the forepart support about an axis in the surface of the pad to increase its inclination moves the end of the support adjacent to the fixed rod away from the rod, means is provided for adjusting the inner box longitudinally of the pad relatively to the outer box, thus enabling the inner end of the forepart support to be maintained under the ball line and adjacent to the rod irrespective of the amount the forepart support is tipped upwardly about its axis.

In the drawings—

Fig. 1 is a side elevation of a pad support embodying the invention with a pad and shoe thereon, parts being partly broken away and in section;

Fig. 2 is a view of one of the rolls forming the blanket between the pad and the support;

Fig. 3 is a side elevation, partly in section, showing the pad support adjusted to a flat position; and

Fig. 4 is an end elevation of the apparatus shown in Fig. 3.

25 The illustrated pad support comprises an outer box having a bottom 20, side walls 22, 23, and a partial end wall 24 at its heel end. Within the box beneath the forepart of a pad 26 of rubber or the like is an inner box having a bottom 28, side walls 30, 31 and a partial end wall 32 at its toward end. The outer box has adjacent to its corners finished surfaces 33 (Fig. 4) engaging similar surfaces on the inner box to facilitate sliding of the inner box relatively to the outer.

30 35 The partial end wall 32 of the inner box (Fig. 3) is connected to an ear 34 on the bottom 20 of the outer box by a screw 36 rotatably mounted in the ear 34 and threaded through the wall 32. On the screw 36 is a knob 38 by which it may be turned to adjust the inner box longitudinally of the outer box. The inner box has a cover 40 which constitutes a support for the forepart of the pad. At each side of the cover is attached by screws 42 a segment gear 44 which has a circular gib 46 arranged to slide in a corresponding groove 47 (Fig. 1) in the inner side of one of the walls 30, 31 of the inner box. Preferably the gear segments 44 are integrally connected by a web 48 and the circular gibs 46 are formed about a center 50 located substantially in the upper surface of the pad where it will be engaged by the ball line of the shoe. At the centers 50 (Fig. 1) on each side of the box there are pins threaded one through each side of the box and extending a short distance into the pad to hold the part of

40 45 50

46 47 51

the pad engaged by them fixed while the front and rear portions are adjusted vertically. Pinions 52 fixed to a shaft 54 journaled in the walls 30, 31 of the inner box mesh with the gear segments 46. One end portion of the shaft 54 extends through a slot 56 in the side wall 22 of the outer box, the slot extending horizontally to permit adjustment of the inner box relatively to the outer.

Loosely mounted on the shaft 54 is a disk 58 having a flat sided hub portion 60 (Fig. 4) fitting the slot 56 so that it can move endwise of the slot but cannot turn therein. A handle 62 fixed to the shaft 54 carries a spring plunger 64 which may engage any one of a series of holes 65 near the periphery of the disk 58.

By pulling the spring plunger 64 out of its hole and turning the shaft 54 by its handle 62, the pinions 52 may be turned to adjust the cover 40 about the center 50. Since upward tilting of the toeward end of the cover 40 about its center moves its lower end away from its position under the ball line, the screw 36 is provided by turning which the cover 40 and the inner box may be moved bodily toward and from the ball line as permitted by the slot 56. Beneath the shank-and-heel portion of the pad is a series of rolls 70 which may be cylindrical or may, as shown in Fig. 2, be small in the middle and gradually increase in size toward the ends, each roll being in form a tore as above explained. The end roll 72 under the ball of the pad is larger than the others and is supported by a rod 74 passing through the sides 22, 23 of the outer box, this rod constituting the only fixed point of the pad support. The rolls 70, 72 are connected at their opposite ends by chains 76 which hold them together as a flexible unit or blanket extending throughout the shank-and-heel portion of the pad.

Beneath the rolls 70 is a block 78 having rectangular portions 79 mounted to slide in ways 80 formed in the inner faces of the sides 22, 23 of the outer box and inclined at about 45° to the bottom 20 of the box. The end and top surfaces of the block 78 which engage the rolls 70, 72 may be complementary to the surfaces of the rolls engaged by them, the end surface 82 being substantially parallel to the ways 80.

The block is moved along the ways 80 by a rack 84 secured at 86 to the block 78 and engaging a pinion 88 fixed to a shaft 90 mounted to rotate in the sides 22, 23 of the outer box. An arm 92 secured to the shaft 90 is provided with a spring plunger 94 similar to the plunger 64 already described which may engage any one of a series of holes 96 formed in the side 22 of the box to hold the block 78 in adjusted position.

The shank portions of the pad 26 may be slotted at 98 to increase the compressibility of the pad in that region.

To control the wrap of the sole at the forepart, the cover 40 has an opening therein shaped like the forepart of a shoe sole but smaller than the forepart of the average shoe, and located in the opening is a plate 100 shaped like the opening. Means for adjusting the plate 100 perpendicularly to the cover 40 is provided by a wedge 102 fixed to the plate 100 and a wedge 104 movable endwise with respect to the wedge 102 and supported by the transverse web 48 integral with the segments 44 to which the cover 40 is secured by the screws 42. A screw 108 rotatably mounted in a lug 110 on the web 48 is threaded into the wedge 104. The screw has a head 112 by which it may

be turned to move the wedge 104 and hence raise or lower the plate 100 with respect to the cover 40. When the plate is flush with the cover a normal amount of wrap will be provided which may be reduced by raising the plate or increased by lowering it.

Having thus described my invention, what I claim as new and desire to secure by Letters Patent of the United States is:

1. A support for a pad for applying pressure to shoe bottoms comprising a support for the forepart of the pad, a support for the shank-and-heel part of the pad comprising a block having an end shaped to support the shank portion of the pad, and a top to support the heel portion of the pad, said block being movable parallel to its shank-engaging end.
2. Apparatus for applying pressure to shoe bottoms comprising a pad, a support for the forepart of the pad movable about a center located in the surface of the pad where the ball line of the shoe engages it, means carried by the support for holding it in adjusted position, and means for moving the forepart support horizontally.
3. A pad support comprising an outer box carrying a support for the shank-and-heel portions of a pad, said support being adjustable in a direction at 45° to the horizontal, an inner box carrying a forepart support adjustable about a center lying substantially in the surface of the pad where it engages the ball line of the shoe, and means for adjusting the inner box longitudinally of the pad.
4. A support for a shoe bottom comprising a pad, a pad box having side walls, a rod supported by the side walls, a series of rolls extending transversely of the box under the shank-and-heel portion of the pad, links connecting the ends of the rolls together and to said rod, a block underlying the rolls, and means for adjusting the block in a direction at a substantial angle to the horizontal.
5. A support for a shoe bottom comprising a pad, a pad box having side walls, a rod supported by the side walls, a series of rolls extending transversely of the box under the shank-and-heel portion of the pad, links connecting the ends of the rolls together and to said rod, a block having an end face inclined to the horizontal and engaging some of the rolls and a horizontal top face engaging other of said rolls, and means for adjusting the block in a direction substantially parallel to its end face.
6. A support for a shoe bottom comprising a pad, a box, a pad support having an inclined end engaging the shank portion of the pad and a horizontal top engaging the heel portion of the pad, and means for adjusting said support relatively to the box in a direction parallel to said inclined end.
7. A support for a shoe bottom comprising a pad, an outer box carrying a support for the shank-and-heel portion of the pad, an inner box having a cover to support the forepart of the pad, said cover being movable about an axis located substantially in the surface of the pad, and means for adjusting the inner box relatively to the outer box longitudinally of the pad.
8. A support for a shoe bottom comprising a pad, an outer box carrying a support for the shank-and-heel portion of the pad, an inner box having a cover to support the forepart of the pad, said cover being movable about an axis located substantially in the surface of the pad, said cover

having segmental gears and said inner box carrying a shaft on which are pinions engaging said segmental gears, said shaft passing through a slot in a wall of the outer box and having a crank arm thereon for turning the pinions, and means for holding the crank arm in adjusted position.

9. A support for a shoe bottom comprising a pad, an outer box carrying a support for the shank-and-heel portion of the pad, an inner box having a cover to support the forepart of the pad, said cover having an opening of the shape of the forepart of a sole, a plate in said opening, and means for adjusting the plate relatively to the cover to control the wrap of a shoe sole pressed on the pad.

10. A support for a shoe bottom comprising a pad, an outer box carrying a support for the shank-and-heel portion of the pad, an inner box having a cover to support the forepart of the pad, said cover being movable about an axis located substantially in the surface of the pad, said cover having an opening, a forepart-shaped plate in the opening, a wedge fixed to the plate, and movable means engaging said wedge for adjusting the plate in the cover opening.

25

11. A support for a shoe bottom comprising a pad, a pad box having side walls, a rod supported by the side walls, a series of rolls each in the shape of a tore extending transversely of the box under the shank-and-heel portion of the pad, links connecting the ends of the rolls together and to said rod, a block underlying the rolls, and means for adjusting the block in a direction at a substantial angle to the horizontal.
12. A support for a shoe bottom comprising a pad, a pad box having side walls, a rod supported by the side walls, a series of rolls each in the form of a tore extending transversely of the box under the shank-and-heel portion of the pad, links connecting the ends of the rolls together and to said rod, a block having an end face inclined to the horizontal and engaging some of the rolls, said block having a horizontal top face engaging others of said rolls, and means for adjusting the block in a direction substantially parallel to its end face.
